NEEDLE BAR FOR FLAT KNITTING MACHINES

Louis Hirsch, Weehawken, N. J.

Application October 1, 1936, Serial No. 103,500

Renewed February 8, 1938

5 Claims. (Cl. 66—114)

This invention relates to a new and useful improvement in needle bars for flat knitting machines and in particular for those of the single unit type upon which stockings are knit complete and in which the central section of the needle bar is swingable out of knitting position so that the knitting of the instep may be suspended without removing the instep loops from the needles while the heel tabs are being knit.

10 In stockings of different sizes the widths of the instep and adjacent foot portions should vary in order to maintain the proper proportions between them so that each will cover the corresponding parts of large and small feet. In present day single unit machines this is impossible because no means is provided for altering the length of the several needle bar sections.

15 It has been suggested that thin needle bar sections be swingably mounted between the swinging and fixed needle bar sections so that one or more of them may be used with either the fixed or swinging sections, as the case may be, by the adjustment of a restraining bolt adapted to bear against the front edges of one or more of these sections. This device has not proved commercially practicable because of the impossibility of maintaining the thin sections in the essential accurate alignment with the other portions of the needle bar or accurately spaced in relation

20 to the other needles.

Another attempt to solve the problem was a needle bar, in which the thin sections are eliminated and a number of complete, swingable central needle bar sections of different lengths supplied, the adjacent rigid sections of the needle bar being adjustable longitudinally to complement the shorter or longer central sections. This device has also failed to meet commercial approval because of the large cost of the many central

25 sections required for even one single machine, the labor and difficulty of replacing one with another, and the difficulty of properly adjusting the rigid sections to secure the extremely accurate needle spacing required and yet leave sufficient clearance

30 for the free swinging of the central section.

35 The invention herein differs from those mentioned in that there are no loosely mounted auxiliary sections as in the first example and no complete replaceable central sections or adjustable rigid sections as in the second example. To the contrary, the rigid and central sections are permanent and positively positioned parts of the needle bar the variations in length being obtained by small sections which can be transferred from

40 the rigid to the central sections or vice versa but

which are positively bolted to the particular section and the needles of which are accurately aligned with the other needles.

The sections are transferable from one section to another without difficulty and are inexpensive. 5 They may correspond exactly in construction to the standard single unit needle bar and because they are positively bolted thereto from an integral part thereof. Thus the invention embodies the essential feature of simplicity, rigidity and accuracy of alignment and the equally important commercial attributes of cheapness, reliability and ease of manipulation.

10 One form of the invention is illustrated by the accompanying drawings, of which

Figure 1 is a front elevation of the needle bar;

Fig. 2 is a plan view thereof showing the central section swung out of knitting position;

Fig. 3 is a view partly in section along the line 3—3 of Fig. 1 viewed as indicated by the arrows;

Fig. 4 is a front view of the right end of the left section of the needle bar with the removable sections detached therefrom;

Fig. 5 is a similar view of the adjacent left end of the central section of the needle bar with the removable sections similarly detached;

Fig. 6 is a sectional view of a part of the left and central needle bar sections on the line 6—6 of Fig. 3 viewed as indicated by the arrows; and

Fig. 7 is a view in perspective of one of the 30 removable needle bar sections; and

Figure 8 is a front view corresponding to Figs. 4 and 5 and showing a modified form of the invention.

As already generally stated and as shown in 35 the drawings the needle bar consists of a swingable section 1 and end sections 2 and 3 which are rigidly bolted to the needle bar support. Each of these needle bar sections consists in general of a face plate, a needle bed grooved as usual to 40 receive the needles 6 and needle clamps. In the case of the swingable section 1 the face plate may be integral with the swingable support 8 which, as is well known, swings upon a pivot such as 9. The needle bed 5 is held against the face plate by 45 bolts 10 and the clamps are held against the needles and needle bed by bolts 11. In short, the general construction of the needle bar sections may be strictly standard. Also the mounting of the central swingable section 1 may conform to 50 standard practice including the automatic locking and releasing mechanism which is indicated at 12 in Fig. 1 but not described since it forms no part of the present invention.

The inner end of each of end sections 2 and 3 55

of the needle bar terminates in a number of short sections 13, 13^a each carrying a number of needles. Similar small sections 14, 14^a, 14^b form a part of the central needle bar section at each end thereof. As shown, each of these sections carries four needles but this may be varied as desired, as may the number of sections. Each section may conform in general to standard needle bar construction, as shown in Figs. 3 and 7. That is to say, each may consist of a face plate 15, needle bed 16 held upon the face plate by a bolt 17 and a needle clamp 18 held in position by a bolt 19. Therefore, each section is a complete needle holding device.

Each section is also drilled as at 20 to permit the passage therethrough of a bolt 21 whereby the small sections may be bolted securely to the remainder of the needle bar sections. Since the clearance between the end and central sections should be only sufficient to permit the central section to swing freely the two small sections 13 and 14 at adjacent ends should be countersunk to receive the heads of bolts 21 as shown in Figs. 1 and 6.

In order to insure accurate alignment a recess 22 is provided in the end sections 2 and 3, a corresponding projection 23 upon one side of all but one, 14, of the small sections, and a corresponding recess 24 upon the other side. Each projection 23 is designed to fit accurately into recess 22 or 24. The projection 23 is omitted from the small sections 14 which constitute the ends of the central needle bar section 1 as shown most clearly in Fig. 5 so that there will be no interference with the closing of the central section 1.

If each of the small sections is of the same length it will be evident that, with the exception of the two sections which are countersunk to receive the heads of bolts 21 they may be shifted so as to make needle bar sections 2 and 3 shorter or longer and to correspondingly lengthen or shorten the central swingable section 1. This is made perfectly clear in Figs. 4 and 5. In Fig. 4 two small sections 13 and 13^a are shown removed from the rest of left end section 2. Section 13 is countersunk to receive the head of bolt 21. To shorten section 2 the left small section 13^a may be removed and the other small section 13^a replaced and rigidly secured by bolt 21, the projection 23 fitting within recess 22. Similarly as shown in Fig. 5 the small sections 14, 14^a, and 14^b may be removed from central section 1, section 13^a added thereto and the four sections replaced and secured by bolt 21^a. Section 1 is provided with a projection 25 which will register with recess 24 of small section 13 or with the similar recess of any other small section. Similar rearrangement will, of course, be made between the right end of section 1 and the left end of section 3 which are also provided with similar small needle bar sections, as shown in Figs. 1 and 2. Therefore, by simply transferring one or more small sections from end sections 2 and 3 to the central section 1 or vice versa, the several sections may be lengthened or shortened symmetrically to any desired degree in steps of four needles more or less to a side depending upon the needle carrying capacity of each small section and the number of small sections provided. When this is done each section of the needle bar is substantially as solid as though made in one piece and functions the same in every way. As previously suggested the number of small sections and the needle capacity of each may conform to the requirements and permit of a wide latitude in in-

step and foot widths without affecting the standard single unit needle bar design in general or the mode of operation of the machine. The essential feature of rigidity and accurate needle alignment are evident and also the commercially equally important features of simplicity and low cost. Needle bars of existing single unit machines may be readily provided with this invention without even altering the standard construction in general of the needle bar itself.

A modified form of the invention is illustrated in Fig. 8 in which the two sets of removable needle bar sections shown in Figs. 4 and 5 are replaced by a pair of similarly removable sections 26 and 27 similar in construction in all respects with the exception that the length of section 26 is equal to the combined lengths of sections 13 and 13^a of Fig. 4 and the length of the other section 27 is equal to the combined lengths of sections 14, 14^a, and 14^b of Fig. 5. In other words, section 26 carries eight needles corresponding to two of the small four needle sections and section 27 carries twelve needles corresponding to three of the small sections. Each of these sections is provided with a groove 24 similar to the groove bearing the same number shown in Figs. 4 and 5, but because of their greater length the rib 23 of the sections shown in Figs. 4 and 5 may be supplanted by another groove 28 and the groove 22 in the end section 2 of the needle bar may be supplanted by a rib 29 corresponding to rib 25 on the other section 1. Thus either one of each pair of removable sections may be attached to either the end or swinging section of the needle bar. The lengths of the pairs of removable sections shown in Fig. 8 may be varied to supply all of the combinations possible with the larger number of small sections shown in Figs. 4 and 5. This form of the invention has the advantage of greater strength and somewhat greater simplicity but the disadvantage of necessitating the carrying in stock of a considerable number of pairs of different needle capacities for each machine. For example, the five small sections shown in Figs. 4 and 5 provide for six different instep widths and they all form a permanent part of the needle bar. To secure a flexibility equivalent to that of the form of the invention shown in Figs. 4 and 5 three different pairs of removable sections would be required only two of which would be attached to the needle bar at one time. Since a standard knitting machine is able to knit say twenty or more stockings at one time and the needle bar for each would require duplicate pairs of removable sections the problem of storing the sections not in use might be troublesome and for that reason the form of the invention shown in Figs. 4 and 5 in which all of the sections form a part of the needle bar at all times is preferred.

What I claim is:

1. A needle bar for a flat knitting machine consisting of a pivoted central section and fixed end sections, said central section terminating at each end in segments positively attached to the remainder of the central section but adapted to be removed therefrom and to be positively attached to the adjacent ends of the fixed sections thereby shortening the central section and correspondingly lengthening the fixed sections.

2. A needle bar for a flat knitting machine consisting of a pivoted central section and fixed end sections, the ends of said central section and the adjacent end of each fixed section each terminating in one or more segments positively attached thereto but adapted to be removed there-

from to shorten it and to be positively attached to the adjacent end of the adjacent section to correspondingly lengthen it.

3. A needle bar for a flat knitting machine according to claim 2 in which the removable segments are bolted directly to the remainder of the 5 corresponding needle bar section.

4. A needle bar for a flat knitting machine consisting of a pivoted central section and fixed end sections, the ends of said central section and the 10 adjacent end of each fixed section each terminating in one or more segments rigidly attached thereto but adapted to be removed therefrom to shorten it and to be rigidly attached to the adjacent end of the adjacent section to correspondingly 15 lengthen it, the non-segmental parts of each section being provided with means cooperating

with means on each segment for securing accurate alignment between the non-segmental and segmental parts.

5. A needle bar for flat knitting machines consisting of a pivoted central section and fixed end sections, the ends of said central section and the adjacent end of each fixed section each terminating 5 in one or more segments rigidly attached thereto but adapted to be removed therefrom to shorten it and to be rigidly attached to the adjacent end of the adjacent section to correspondingly 10 lengthen it, the non-segmental part of each section and also each segment being provided with means for securing accurate alignment between associated segments and between such segments and the non-segmental part of the section. 15
